ATTORNEY

UNITED STATES PATENT OFFICE

BERTRAM E. MESLER, OF BROOKLYN, NEW YORK

SHADE-ROLLER STOP

Application filed July 12, 1929. Serial No. 377,811.

This invention relates to improvements in shade roller stops.

The primary object of the invention resides in an automatic shade roller stop for stopping the upward winding movement of a shade upon its roller to prevent the free end of the shade from idly spinning about the roller, which causes accidental unwinding of the shade roller spring resulting in its loss of tension.

Another object of the invention is to provide a shade roller stop which may be applied to shade rollers now in use without altering the construction of the shade roller, and which may be set at the time of its attachment to stop the winding of the shade at a predetermined point.

A further object of the invention is the provision of a shade roller stop for attachment to one end of a shade roller and with which the shade roller supporting bracket coacts to effect stopping of the winding movement of the roller.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is a perspective view of a shade roller provided with my improved stop and shown mounted upon a window casing.

Figure 2 is an enlarged vertical longitudinal sectional view through one end of the shade roller showing the parts in position when the shade is lowered.

Figure 3 is a view similar to Figure 2 but showing the position of the parts when the shade is at the limit of its winding.

Figure 4 is a vertical transverse sectional view on the line 4-4 of Figure 2.

Figure 5 is a collective perspective view of the several parts constituting my invention.

Referring to the drawing by reference characters, the numeral 10 designates a shade roller having a flexible shade 11 windable thereon, while the free edge 12 carries

the usual reinforcing strip from which a pull cord 13 depends. The roller is hollow for the purpose of housing a helical spring 14 which when wound up, places the roller under tension for winding the shade from a lowered position to a raised position. The usual ratchet mechanism (not shown) is provided for locking the shade in a lowered position against winding, but it is not believed necessary to go into a specific explanation regarding the same as this feature is present on the types of shade rollers now in common use. A flat trunnion 15 extends from one end of the roller 10 and fits into a supporting bracket 16 fixedly secured to one of the sides of the window casing 17. Although I have only mentioned the means of supporting one end of the shade roller upon the window casing, it will be appreciated that the opposite end is supported in the usual manner.

Fixed to the shade roller 10 adjacent the end supported in the bracket 16, is a collar 18, the inner walls of which are provided with longitudinal keys 19 for embedment in the wooden roller 10, while tacks 20 pass through the collar 18 into the roller for rigidly connecting the collar therewith. Diametrically opposed lugs 21 extend from the exterior of the collar into an elongated slot 22 provided in opposed ears 23 extending from a sleeve member 24. The interior walls of the sleeve member are screw threaded as at 25 for threaded engagement with the exterior threads 26 provided on a screw cap 27. The end wall of the cap 27 is provided with an elongated slot 28 through which the flat trunnion 15 extends in order that the cap member fits over the end of the roller, as clearly shown in Figures 2 and 3 of the drawing. It will be seen that both the collar 18 and the screw cap 27 rotates with the roller 10 which imparts a longitudinal sliding movement to the sleeve 24, although the sleeve 24 also turns but simultaneously slides in a longitudinal direction.

Assuming that the shade 11 is in lowered position at which time the parts are as shown in Figure 2 of the drawing wherein the outer

end of the sleeve 24 is in spaced relation to the shade bracket 16 and the lugs 21 are adjacent the inner end of the slots 22. Upon the actuation of the pull cord 13 to release the ratchet mechanism, the spring 14 imparts a winding movement to the roller 10 and during this winding movement, the sleeve 24 is fed outwardly until the outer end of the sleeve contacts with the bracket 16, thus arresting movement and bringing the roller to a stop. The engagement of the sleeve 24 with the bracket 16 also prevents accidental jumping of the shade roller from its bearings as the action of the spring tends to jam the opposite ends of the roller against the respective brackets. It will, of course be understood, that the attachment may be set to bring the roller to a stop just prior to the full winding of the shade thereon and which is accomplished by adjusting the screw cap 27 relative to the sleeve 24 before attachment of the parts to the shade roller.

From the foregoing description, it will be seen that I have provided a shade roller attachment which may be installed upon shade rollers now in use without altering the construction thereof and which automatically stops the winding of a shade at a predetermined point during its winding movement which prevents "spinning" of the free edge of the shade when fully wound. The invention also eliminates the necessity of re-winding the roller spring now caused by accidental spinning of the shade upon the roller.

The screw cap 27 in addition to forming the above functions also serves to protect the end of the shade roller against rust as the same fits over that end of the roller containing the ratchet mechanism usually present in spring actuated shade rollers. In some instances, rust accumulates upon the working parts of the ratchet and renders them inoperative. The cap therefore serves to overcome this defect.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In combination with a shade roller and its support including a supporting bracket, a stop member movable by turning movements of the roller relative to said bracket and moving toward said bracket on turning the roller in one direction and away from said bracket on turning the roller in the opposite direction, and means carried by said roller and correlated with said stop member

for actuating the same upon rotations thereof in both said directions.

2. In combination with a shade roller and its support including a supporting bracket, a collar fixed to said roller, a threaded member fixed to said roller, a sleeve member fitting over said threaded member and being internally screw threaded for co-acting engagement with said threaded member, and means for operatively connecting said collar with said sleeve member so as to turn together but to permit said threaded member to longitudinally feed said sleeve member into and out of frictional engagement with said supporting bracket upon rotations of said shade roller in one direction and in the opposite direction. 70 75 80

3. A stop attachment for shade rollers comprising a key-carrying structure adapted to be secured to a shade roller adjacent one end thereof, an exteriorly threaded member adapted to fit over the end of a shade roller to turn therewith, an internally threaded sleeve threadedly connected to said threaded member, there being a key-way carried by 90 said sleeve, and co-acting means including said fixture and key-way operatively connecting said collar with said threaded sleeve for causing the same to simultaneously turn and for permitting longitudinal movement 95 of said sleeve by said exteriorly threaded member. 85

4. A stop attachment for shade rollers comprising a structure adapted to be fixedly connected to a shade roller adjacent one end thereof, an exteriorly threaded member adapted to fit over the end of a shade roller to turn therewith, an internally threaded sleeve threadedly connected to said threaded member, and co-acting means operatively connecting said structure with said threaded sleeve for causing the same to simultaneously turn and for permitting longitudinal movement of said sleeve by said exteriorly threaded member, said means including an elongated slot provided in said threaded sleeve. 100 105 110

5. In a shade roller having a flat projecting trunnion at one end thereof, a threaded cap member provided with a slot in its end wall 115 for the passage of said flat trunnion, said cap member fitting over the end of said roller, a collar fixed to said roller inwardly of said cap member, a sleeve member internally screw threaded for co-acting engagement with exterior threads provided on said cap member, and lugs extending from said collar into elongated slots provided in said sleeve member, substantially as and for the purpose specified. 120 125

In testimony whereof I have affixed my signature.

BERTRAM E. MESLER.
